UNITED STATES PATENT OFFICE.

HUGH CHRISTIE, OF MELROSE, NEW YORK, ASSIGNOR TO THE BIGELOW CARPET COMPANY, OF CLINTON, MASSACHUSETTS.

DESIGN FOR A CARPET.

SPECIFICATION forming part of Design No. 11,869, dated July 13, 1880.

Application filed February 19, 1880. Term of patent 3½ years.

To all whom it may concern:

Be it known that I, HUGH CHRISTIE, of Melrose, in the county and State of New York, have invented a new and Original Design for 5 a Carpet, of which the following is a specification.

This invention relates to a new design for carpets, oil-cloths, and analogous fabrics; and it consists in the novel grouping and configuration of figures, hereinafter more fully described and claimed.

The accompanying photograph illustrates my new design.

On the background of the carpet is a central 15 rectangular border, A, inclosing a field on which is a group of flowers, B, with sprays extending over the border A to the surrounding figures.

C is an obliquely-placed figure formed of a number of parallel lines of ornamentation. Said 20 figure partially overlies one corner of the border A, with which it is otherwise connected by a spray of flowers and leaves, a, extending to it from the group B. On the figure C are other sprays and flowers, which connect it with surrounding figures.

D is a group of flowers inclosed by a rectangular border, d, which overlaps the border A, and having sprays extending outward and connecting it with the surrounding figures.

E is a field inclosed on one side by an arched border, e, and by the figure C, and in which is a group of flowers, h, which connect the said field with the surrounding borders and figures, and on which field E is also a spray, i, of flowers and leaves. The other side or part, J, of the field E has borders m n and a group, k, of flowers that connect said borders. The group k joins the group h of flowers when the carpet 35 is matched.

F is an arch-shaped field inclosed by arched borders e f, and at the base at one side by parallel ornamented borders j, with a spray of

flowers, l, superposed thereon, and at the other side by triangular figures G.

I is a group of flowers and leaves on field F, 45 with sprays extending outward and connecting with the surrounding borders and figures.

H is a triangular figure connected with the figures A C d and the groups of flowers B D.

I claim—

1. The design for a carpet, consisting of the rectangular border A and the group of flowers B, substantially as shown.

2. The design for a carpet, consisting of the obliquely-placed figure C and superposed 55 sprays of flowers and leaves, substantially as shown.

3. The design for a carpet, consisting of the border A, figure C, group of flowers B, and connecting-spray a, substantially as shown.

4. The design for a carpet, consisting of the group of flowers D and border d, substantially as shown.

5. The design for a carpet, consisting of the group D, borders d A, and group B, substantially as shown.

6. The design for a carpet, consisting of the triangular figure H, figure C, groups D B, border d, and border A, substantially as shown.

7. The design for a carpet, consisting of the 70 field E J, flowers h k, and spray i, figure C, and border e, substantially as shown.

8. The design for a carpet, consisting of the field F, borders e f j, triangular figures G, and floral group I, substantially as shown.

9. The design for a carpet, consisting of the borders A d e f i j m n, floral groups B D h I K, fields E, J, and F, and figures C G H, substantially as shown.

HUGH CHRISTIE.
